Inventor
Halsey D. Walcott

UNITED STATES PATENT OFFICE.

H. D. WALCOTT, OF BOSTON, MASSACHUSETTS, ASSIGNOR TO H. WILLIAMS, OF SAME PLACE.

EYELET-MACHINE.

Specification of Letters Patent No. 27,674, dated March 27, 1860.

To all whom it may concern:

Be it known that I, HALSEY D. WALCOTT, of Boston, in the county of Suffolk and State of Massachusetts, have invented an Improved Eyelet Machine or Instrument for Setting Eyelets, of which the following is a full, clear, and exact description, reference being had to the accompanying drawings, making part of this specification, in which—
10 Figure 1 is a view of my improved instrument. Figs. 2 and 3 details to be referred to hereafter.

In attaching eyelets to articles of wearing apparel, or where they are used to secure articles (such as sheets of paper) together, a punch is employed to make a hole for the reception of the eyelet, and a closing die is used to set the eyelet after it is inserted.

My present invention consists in a convenient portable instrument for this purpose embracing in one tool both punch and setting die.

That others skilled in the art may understand and use my invention I will proceed to describe the manner in which I have carried out the same.

In the said drawings the two levers A, B, pivoted together at *a* form a pair of pincers, the jaws *b*, *c*, of which are widened out at their ends. The jaw *b*, has attached to and rising from its inner face, at one corner the cylindrical plunger *e*, and at the other corner the setting punch or die *f*. To the inner face of the jaw *c*, is pivoted at *a* piece *g* (detached in Figs. 2 and 3) which is free to oscillate toward either side of this jaw, except when confined by a thumb screw *h*, which passes through a curved slot *i* in the jaw, and screws into the piece *g*. This piece *g* is much narrower than the jaw *c*, and carries at its outer end a cylindrical die *r*, having a hole *k* made through it and through the piece *g* of a suitable size to receive the plunger *e*; and also another die *l* the recess of which is of a contour corresponding with the setting punch *f*.

A notch *m* is cut out of the jaw *c* near one side to allow the material punched out by the plunger *e* to fall out from the hole *k*. A spring *n*, secured at *6*, to the face of the jaw

b, has a ring at its outer end which embraces the plunger *e*, and serves to clear it of the material through which the plunger has passed.

The following is the operation of this instrument: The piece *g*, being in the position shown in Fig. 1, with the die *r*, immediately over the plunger *e*, and the screw *h*, turned down to secure it in place—the necessary holes may be punched or cut out from the material in which the eyelets are to be inserted. It will be perceived that while this is being done the space above the die *f* is free, so that other portions of the goods will not be marred by it when the jaws *b* and *c* are shut toward each other. When the requisite holes have been made, the screw *h*, is loosened and the piece *g* is swung over to the other side of the jaw *c*, this brings the die *l*, over the die *f*, when the pincers may be used to close down or set the eyelets which have been inserted in the holes prepared for them; the space over the plunger *e*, now being clear, so that it will not injure the goods.

The plunger *e*, and die *r*, here represented are such as are generally used for paper and light articles, but for leather a different punch would be used, but as I make no claim to the form of punch this change will not affect the spirit of my invention.

Other devices may be employed for securing the piece *g* in place—for example, a spring may be attached to the top of the jaw *c*, having a pin projecting from its outer end, which will fall into a suitable notch in the piece *g*, and hold it, then by raising this spring the piece *g* will be free to move from one side to the other of the jaw *c*.

What I claim as my invention and desire to secure by Letters Patent is—

1. The nippers A, B, having their jaws *b*, *c*, furnished with both a punch or cutter, and a closing or setting die, substantially as described.

2. I claim the adjustable piece *g* operating substantially as specified.

HALSEY D. WALCOTT.
